Charles W. Ernst, St. Paul, Minn., assignor to Brown & Bigelow, St. Paul, Minn.

Application April 1, 1954, Serial No. 29,803

Term of patent 14 years

(Cl. D44—10)

To all whom it may concern:

Be it known that I, Charles W. Ernst, a citizen of the United States, residing in St. Paul, county of Ramsey, and State of Minnesota, have invented a new, original, and ornamental Design for a Tray or Similar Article, for which the following is a specification, reference being had to the accompanying drawings forming part thereof.

I claim:

The ornamental design for a tray or similar article, as shown.
